UNITED STATES PATENT OFFICE.

SAMUEL B. WILLIAMS, OF BROOKLYN, NEW YORK, AND EARL S. GIBSON, OF RIDGEWOOD, NEW JERSEY, ASSIGNEES TO WESTERN ELECTRIC COMPANY, INCORPORATED, OF NEW YORK, N. Y., A CORPORATION OF NEW YORK.

TELEPHONE-EXCHANGE SYSTEM.

Application filed June 25, 1924, Serial No. 722,215. Renewed April 5, 1926.

This invention relates to telephone exchange systems in general and more specifically to such systems wherein automatic switches are employed for the establishment 5 and completion of connections.

In telephone systems where switches of the coordinate type are employed and these switches are selectively operable in accordance with the setting of a common controlling mechanism it is necessary that the controlling mechanism be associated with the proper switch or group of switches in which a selected trunk terminates. Furthermore, when the trunks of a group leading from a 10 selector switch are divided and terminate in a number of succeeding equivalent switches, it becomes necessary to associate the controlling mechanism not only with the proper one of the latter switches but also with the particular division of the group of selected 15 trunks terminating in this switch.

Accordingly it is an object of this invention to provide an improved means for associating controlling mechanisms with selectively operable switches for controlling such 20 switches.

It is a further object of the invention to provide an efficient means for testing and connecting to any one of a group of unnumbered P. B. X. lines.

A feature of the invention relates to the use of a common testing mechanism which is associable with a number of trunks for the purpose of selecting an idle one thereof and 30 for locating the particular switch or portion of the switch wherein the idle trunk terminates.

A further feature of the invention relates to means for selecting a group of trunks at 40 a first selective switch and for simultaneously setting up a record, in a controlling sender, of the location of this selected group, to subsequently associate a common controlling mechanism with the second selective switch to which the trunks of this selected group lead.

Another feature of the invention relates to the means for testing and completing connections to unnumbered lines such as those 50 leading to private branch exchanges.

Referring to the drawings, Figs. 1 to 17 55 when arranged in the order shown in Fig. 19 illustrate circuits and apparatus in sufficient detail to give an understanding of a preferred form of carrying out the invention.

Fig. 1 in the upper left hand portion 60 shows a subscriber's line terminating in contacts of a coordinate line switch. Outgoing from this line switch are a number of district selector trunks, one of which is shown in detail. In the center portion of this figure 65 is shown one of a number of coordinate sender selector switches for associating calling subscribers' lines with a registering and controlling sender such as is shown, part schematically and part in detail, below the 70 broken line.

Fig. 2 illustrates one of a number of coordinate district selector switches together with groups of trunks outgoing therefrom.

Fig. 3 above the broken line shows one of 75 a number of local incoming trunks leading from the district switch. These trunks are employed in completing local connections. Below the broken line is disclosed one of a plurality of coordinate office selector 80 switches for extending calling lines to distant offices.

Fig. 4 illustrates a coordinate local incoming or second selector switch and groups 85 of trunks outgoing therefrom, together with certain controlling equipment.

Fig. 5 illustrates a final selector or connector switch in which called subscribers' lines terminate and in which lines leading to a private branch exchange also terminate. 90

Fig. 6 illustrates a sender connector device for associating a selected sender with an idle common controlling mechanism or outgoing marker.

Fig. 7 to the left shows a district frame 95 connector while to the right is shown the district trunk connector.

Fig. 8 to the left shows an office frame connector and to the right an office trunk connector.

Fig. 9 to the left of the broken line shows 100 an incoming frame connector. To the right of the broken line is shown a final trunk connector.

Fig. 10 at the upper left portion shows a final frame connector. The remainder of this figure shows a final translator.

Fig. 11 shows the register and translator portions of an outgoing marker.

Fig. 12 shows the controlling equipment of the outgoing marker.

Fig. 13 shows testing equipment located in the outgoing marker.

Fig. 14 shows testing and controlling equipment of the incoming marker which controls the selective operation of the incoming and final switches.

Fig. 15 shows a final translator connector for connecting any of the incoming markers to any of the final translators, one of which is shown in Fig. 10.

Fig. 16 shows a sender connector for connecting the register senders to the incoming markers.

Fig. 17 shows the register equipment located in the incoming marker.

Fig. 18 illustrates in schematic form the arrangement of the circuits and apparatus shown in detail in Figs. 1 to 17, inclusive.

Referring to Fig. 18 it will be seen that the subscribers' lines enter the exchange and have an appearance in the contacts of a number of line switches such as 1801. Terminating in other contacts of the line switches and outgoing therefrom are a number of district selector trunks 1802, 1813. The trunks outgoing from the line switches terminate in contacts of district selector switches, such as 1803, 1804, etc., which are arranged in groups.

It will be observed that certain of the trunks outgoing from the district selector switches, as the group of trunks 1805, lead to office selector switches 1806, 1807, etc.

The arrangement is such that the total number of any group of trunks extending between any district switch as 1804 and any office switch as 1806 is divided. Part of the group appears in one office switch while the remainder of the group appears in a second office switch. Thus a portion of the trunk group 1805 leads to switch 1806 while another portion leads to the switch 1807. Other trunks are also provided for the purpose of establishing local connections. These are represented by the trunk groups 1808, 1809, 1810, etc. In a manner similar to that described, these local incoming trunks are distributed among a number of incoming switches 1811 and 1812, etc. Thus the trunks of group 1809 are divided between incoming switches 1811 and 1812.

The trunks as 1802, 1813, etc., outgoing from the line switches also have an appearance in the sender selector switch 1814 whose function it is to associate an idle one of the senders 1815, 1816 with a calling line. The selected idle sender is then connected by means of the device 1817 to an idle outgoing

marker. Two of these markers 1818, 1819 are shown.

For the purpose of associating the outgoing markers with the district switches there are provided a number of district frame connectors as 1820. The outgoing markers are also associative with the trunks leading from the district switch by means of trunk connectors as 1821. When a particular district frame and a group of trunks outgoing therefrom have been associated with an outgoing marker, a test is made therein to determine an idle trunk and an idle link in the district switch. At the same time a test is being made to determine the particular switch to which this idle trunk leads and to the particular part of the group to which this trunk belongs.

Let it be assumed, for example, that a calling subscriber has obtained connection through line switch 1801 and one of the trunks 1802 to the district switch 1803. Let it be further assumed that the translation of the called line record in the marker has caused the selection of a trunk in a group 1810, trunk 1829, for example. While the outgoing marker was making the test of the trunks in group 1810, a record was being transmitted to the incoming switch registers of the sender. This record of the incoming frame in which trunk 1829 terminates is determined conjointly by the operation of a district trunk connector as 1821 and the particular manner in which the testing equipment located in the marker is operated.

When the connection has thus been completed through switch 1803 to the trunk 1829 and a record set up in the sender identifying the local incoming switch 1811, the outgoing marker and sender connector as well as the trunk and frame connectors are released and revert to common use.

The sender connector 1824 is next actuated to connect the register sender with an idle incoming marker such as 1825 whereupon the numerical portion of the called line designation is transferred from the sender registers to the registers of the incoming marker. At this time the record of the incoming switch in which trunk 1829 terminates is also transferred from the incoming frame registers of the sender to the incoming frame registers of the marker. The incoming marker now proceeds under control of this transferred record to operate the proper incoming frame connector as 1826 which will give the marker access to the frame 1811. The marker having thus been associated with the proper frame, and having identified the proper group of trunks extending between incoming and final frames, causes the operation of the final trunk connector 1827. A test is now made in the incoming marker to determine an idle link in switch 1811, an idle trunk in 130

the selected group of final trunks and an idle link in switch 1828 giving access to the called line. When this three point test has been made and the called line selected, the incoming marker, sender, and the various connectors are released and revert to common use.

Should the number as dialled by the calling subscriber necessitate extension of the calling line to a distant office, the procedure is similar to that above described as far as the point where the outgoing marker tests the selected group of trunks leading from the district switch. In this case, however, connection through an office switch is completed before the marker is released. It is therefore unnecessary to transmit to the sender a record of the office switch wherein a particular selected trunk appears. If, for example, the translation of the office code in the outgoing marker causes the selection of trunk 1832 belonging to group 1831, the district trunk connector 1821 in conjunction with the testing equipment of the marker will not only identify the proper office switch as 1806 but will give an indication of the portion of the group 1831 to which trunk 1832 belongs.

From the foregoing description it will be seen, therefore, that whenever a trunk group is arbitrarily divided between a number of switches the marker simultaneously tests this trunk group and identifies the proper switch to which an idle one of this group of trunks leads.

Referring to Figs. 1 to 17, a detailed description will now be given of the construction of the several switches and controlling mechanisms, as well as their method of operation. The line switch 100, sender selector 150, district switch 200, office switch 300, incoming switch 400 and final switch 500 may be of the same general construction and operation as the switches shown and described in detail in the patent to S. B. Williams, No. 1,517,331, issued December 2, 1924.

The sender connectors 600 and 1600 consist of a number of multi-contact relays, certain of these relays being individual to markers and others being individual to controlling senders. Thus, relay 601 is individual to the sender shown in Fig. 1, while relay 602 is individual to the outgoing marker illustrated in Figs. 11, 12 and 13. Similarly, relay 1602 is individual to the sender shown in Fig. 1 and relay 1601 is individual to the incoming marker shown in Figs. 14 and 17. As hereinbefore mentioned, there are provided a number of frame connectors, for example, the district frame connector 700 is individual to the group of district switches, including switch 200. Similarly office frame connector 800 is individual to the group of office switches,

including switch 300 and the incoming frame connector 900 is individual to the group of incoming switches, including switch 400. In addition, there are provided trunk connectors, as district trunk connector 70 750, office trunk connector 850, and final trunk connector 950. The purpose of the trunk connectors is to associate all the trunks of a selected group with the marker testing mechanism, which then proceeds to 75 locate an idle trunk for the purpose of extending the calling line.

When an office switch is not capable of accommodating the total number of trunks outgoing from a vertical row of contacts 80 in the district switches this group is divided between one or more office switches. For example, if there are 69 trunks in a group leading from the vertical row of contacts 230, then 50 of these trunks are terminated on one office switch as 300, the remaining 19 trunks being extended to a second office switch which may accommodate one or more groups of 19 trunks. If all the trunks leading from a vertical row of contacts in the district switch are terminated on one office frame, then as soon as the office code is translated in the marker to identify the district trunk group desired, the marking of this group would at the same time 95 identify the proper office frame connector to be used. However, in cases where the trunk groups are divided it becomes necessary to know not only the group in which a selected trunk occurs, but also the particular portion of this group. This identifying means is controlled by the district trunk connector and the marker testing mechanism, as will be described in detail hereinafter.

In a similar manner when the nature of the call requires extension of the calling line through a local incoming switch and where the group of trunks leading from the district switch is divided between a number of incoming switches, the particular portion of the selected group of trunks must be identified. The means for starting the proper incoming frame connector is modified in this instance, because the outgoing 105 marker is discharged as soon as selection has been completed through the district switch and before an incoming marker is associated with the sender. The test is similar to that described above, except that a 110 record is transferred by means of the district trunk connector and the marker testing mechanism to the sender; this record is subsequently re-transferred to an incoming marker to cause the operation of the proper 115 incoming frame connector.

It is thought that a better understanding of the nature of the invention will be obtained from a detailed description of the method of operation. For this purpose let 120

it be assumed that the subscriber at station 101 has initiated a call for the purpose of communicating with a subscriber whose line is located in a distant office, reached by 5 means of a switch as 300.

Selection through an office selector.

The removal of the receiver by the calling subscriber causes his line to be extended 10 through the line switch 100 to the district trunk 102. At the same time the sender selector 150 is actuated to associate an idle sender with the calling line. The association of a sender causes relay 103 to operate. 15 The circuits are now in readiness to receive impulses dialled by the calling subscriber. The wanted line designation corresponding to these impulses is recorded upon the registers 190 of the sender. At this time 20 ground is extended over conductor 151 through the left winding of relay 603 to battery at the lower outer armature and contact of relay 604. For a detailed description of the manner in which these latter operations 25 are effected, reference may be had to the application of W. W. Carpenter, Serial No. 703,362, filed April 1, 1924. Relay 603 closes a locking circuit for itself through its right hand winding in series with the winding of 30 relay 604, which operates. Relay 604 is a common relay and by its operation prevents more than one connection being completed at a time through connector 600. A circuit is now completed for operating multi-contact 35 relay 601 traceable from battery through the winding thereof, left armature and contact of relay 603, upper outer armature and contact of relay 616, to ground at the lower inner armature and contact of relay 604. Assuming the marker associated with relay 605 40 to be busy, then relay 606 individual thereto is operated. A circuit is thereupon completed from battery at the outer armature and contact of relay 608, left winding of relay 607, armature and back contact of relay 609, left armature and contact of relay 610, armature and locking contact of relay 606, inner armature and contact of relay 616 45 to ground at the armature of relay 604. Relay 607 operates in this circuit and completes a locking circuit for itself in series with the winding of relay 608 which also operates. The operation of relays 607 and 608 completes an obvious operating path for 50 relay 609. The operation of relay 609 renders the marker associated therewith non-selectable by other senders. A circuit is now completed from battery through the winding of multi-contact relay 602, right intermediate armature and contact of relay 607 to ground at the armature and contact of relay 608. 55 With relays 601 and 602 operated, the sender is connected to the outgoing marker shown in Figs. 11, 12 and 13, whereupon

the marker ground control relay 1201 is operated. The circuit for operating relay 1201 may be traced from battery through its winding, conductor 1250, contacts of connector 600 to the conductor 152, which is 70 grounded in the sender. Relay 1201 locks in a circuit completed through its winding and locking contact, through the right outer armature and back contact of relay 1202, right outer armature and contact of relay 1204 to ground at the left inner armature and back contact of relay 1203. In a manner similar to that described in detail in the above mentioned application of W. W. Carpenter, Serial No. 703,362, filed April 1, 80 1924, ground is extended through the right outer armature and contact of relay 1201, right inner armature and back contact of relay 1204, right outer armature and contact of relay 1205, left armature and contact 85 of relay 1206, conductor 1251, contacts of connector 600, conductor 154 through the operated relays in the sender register 190, thence over the group of conductors 650 through the windings of corresponding 90 marker register relays. In the manner described in the above mentioned application of W. W. Carpenter, Serial No. 703,362, filed April 1, 1924, ground is also extended over conductor 153 through contacts of unoperated 95 register relays in the sender to cause the remaining marker register relays to operate. When all the relays 1100 have operated the grounded conductor 1251 is extended through the upper armatures and 100 contacts of all the register relays in series to battery through the winding of relay 1102. Relay 1102 operates and closes a locking circuit for itself through the normal contacts of relay 1101 to the grounded conductor 1251. Relay 1102 also completes an obvious 105 operating circuit for relay 1101. Relay 1101 locks through its right inner armature and contact to the grounded conductor 1251, causing the release of relay 1102. 110 When relay 1102 operated the marker register relays corresponding to unoperated sender register relays are released. For the purpose of description, let it be assumed that relays 1103, 1104, 1105 and 1106 remain operated. Relays 1103 and 1104 represent the 115 registration of the first digit of the office code, relay 1105 the second digit, and relay 1106 the third digit.

A circuit is now completed from battery 120 through the winding of translator relay 1107, lower inner armatures and front contacts of relays 1104 and 1108, lower inner armatures and back contacts of relays 1116 and 1117 in series, through the left armature and contact of relay 1101 to the grounded conductor 1251. Multi-contact relay 1108 also operates at this time in a circuit traceable from battery through its winding, lower inner armature and front 130

- contact of relay 1106, lower inner armature and in contact of relay 1118 to the above traced ground. When relay 1108 operates a circuit is closed from battery through the 5 winding of multi-contact relay 1109, through the connecting block 1110, contact of relay 1108, lower outer armatures and back contacts of relays 1119 and 1120 in series, lower outer armature and contact of relay 1105, lower outer armature and back contact of relay 1121 to the grounded conductor 1251 above traced. With the translator relays operated in accordance with the recorded office code a circuit is completed for 10 relay 1207 which is individual to the desired group of trunks leading from the switch 300. The circuit for this purpose may be traced from battery through the winding of relay 1207, thence by means of 15 the connecting blocks 1261 and 1262, conductor 1252, through the connecting block 1111, contact of relay 1109, lower armature and contact of relay 1107, conductor 1153, to ground at the left outer armature and contact of relay 1205. Relay 1207 immediately 20 closes a circuit through its winding and locking contact, the right inner armature and back contact of relay 1204 to ground at the armature of relay 1201. Relay 1207 completes a circuit from battery through the winding of relay 1208, thence by means of connecting blocks 1261 and 1262 through the left outermost armature and contact of 25 relay 1207, right intermediate armature and contact of relay 1202, right outer armature and contact of relay 1205 to ground as above traced. Relay 1208 is individual to the group of trunks leading from the district switch 200, giving access to the group of 30 trunks identified by relay 1207.
- Since the nature of this call requires extension of the calling line to a distant office, the translator mechanism causes the operation of relay 1112 in a circuit which may 35 be traced from battery through its winding, thence by means of the connecting block 1111, through contacts of relays 1109 and 1107 to the grounded conductor 1153. With relay 1112 operated, a circuit is closed from 40 battery through the winding of relay 1306, conductor 1357 to ground at the armature of relay 1112. Relay 1306 locks through its winding and locking contact, conductor 1258, right inner armature and back contact of relay 1204 to ground at the armature of relay 1201. Relay 1306 by its operation serves as an identification to the marker that the class of 45 calls is one requiring the use of an office selector switch as 300.
- When relay 1101 operated a circuit was closed to start the operation of the district frame connector 700, associated with the group of district switches including switch 50 200. This circuit may be traced from bat-
- tery at the right outer armature and contact of relay 1206, conductor 1253, winding of relay 701, conductor 1263, armature and back contact of relay 1215, conductor 1264, right outer armature and contact of relay 1101, conductor 654, contacts of connector 600, thence through mechanism in the sender to the grounded conductor 154. Relay 701 completes a circuit traceable from battery through the right winding of relay 702, 55 armature and front contact of relay 701, armature and back contact of relay 703, upper armature and back contact of relay 704 to ground at the armature and contact of relay 705. Relay 705 also operates at this time over a circuit completed from battery through its winding, lower armature and back contact of relay 704, right armature and contact of relay 702, conductor 751, left outer armature and contact of relay 1209, right intermediate armature and contact of relay 1202, right outer armature and contact of relay 1205 to ground through the right inner armature and back contact of relay 1204. When relay 705 operates it 60 breaks the original energizing circuit for relay 702, but this relay being slightly slow to release remains locked through its left winding in series with the winding of relay 704 to ground at the armatures of relay 705. Relay 704 operates in this last traced circuit, opening the energizing circuit of relay 705 which begins to release. When relay 705 has released multi-contact relay 706 65 operates over a circuit traceable from battery through its winding, left outer armature and contact of relay 702, upper armature and front contact of relay 704 to ground at the lower armature and back contact of relay 705. After relay 705 releases 70 relays 702 and 704 remain locked through the lower front contact of relay 704, right contact of relay 702 to ground over conductor 751. 75
- Vertical magnet 257 now operates from battery through its winding, conductor 250, left armature and back contact of relay 104, contacts of sender selector 150, contacts of connector 600, conductor 651, right normal contacts of relay 1211, left inner armature and back contact of relay 1212, conductor 1254, contacts of frame connector 700, returning thence to the grounded conductor 751. Magnet 257 operates and rotates rod 216 to prepare the vertical row of contacts 80 210. Magnet 257 also extends the above traced ground through its inner armature and contact to conductor 251, and thence to battery through the winding of multi-contact relay 707. A circuit is now completed from battery through the winding of relay 1211, left outer armature and back contact of relay 1212, conductor 752, contacts of connector 700, returning thence to conductor 1254, left inner armature and back contact 85 130

of relay 1212, normal contact of relay 1211 to the grounded conductor 651. Relay 1211 in operating, opens the original energizing circuits for magnet 257 and relay 707 but a 5 substitute holding circuit is now provided which is traceable through the right armature and front contact of relay 1211.

Magnet 257 also completes an obvious circuit for the common horizontal link magnet 10 217. With magnet 217 operated, connection is completed through the link 218 and relay 104 operates in a circuit traceable from battery through its winding, conductor 161, contacts of link 218, conductor 252, contacts 15 of connector 700, conductor 754, left armature and contact of relay 1211 to ground at the armature of relay 1205.

While the latter operations were taking place, the district trunk connector 750 was 20 being actuated. When relay 1208 operated it completed a circuit for the start relay 708. This circuit may be traced from battery through the winding of this latter relay, conductor 755, left outer armature and contact of relay 1208, conductor 1255, left intermediate armature and contact of relay 702 to ground through the upper armature and front contact of relay 704. In a manner similar to that described in connection with 25 the connector 700, relay 708 brings about the operation of multi-contact relay 709. The district trunk group relay 1208 now causes the operation of relay 710 which is individual to the selected group of district trunks. 30 The circuit for this purpose may be traced from battery through the winding of relay 710, conductor 1265, left armature and contact of relay 1208 to ground through the right intermediate armature and contact of 35 relay 708. With connectors 700 and 750 operated, a circuit is closed for energizing trunk vertical magnet 228. This circuit is completed from battery through the winding of magnet 228, conductor 253, contacts 40 of connector 700, conductor 756, next to the left inner armature and contact of relay 1208, conductor 1266, contacts of connector 750 and returning thence to the grounded conductor 751.

Frame connector 700 in operating connects 50 the group of test and controlling conductors 260 to the marker test relays 1300. In a similar manner, trunk connector 750 extends the test connectors of the selected group of 55 trunks to the same testing relays. It will be observed that the left windings of test relays 1301, 1302, etc., are connected to the test conductors of the links in switch 200, while the right windings of these test relays 60 are connected to the test conductors of the selected group of outgoing trunks including trunks 270, 271, 272, etc. If either a link or trunk or both link and trunk are busy, the test relay connected thereto is operated.

65 Let it be assumed that the number of

links in switch 200 is 69 and that there are 69 trunks outgoing from each vertical row of contacts. If, however, the capacity of the office switch 300 is such as to be capable of accommodating only 50 of these trunks, 70 some indication must be given as to whether the selected district trunk is in the first fifty or in the last nineteen. Since the first fifty trunks are terminated on one office selector switch while the remaining 19 are terminated 75 at a different office switch, this indication is controlled by the marker testing equipment shown in Fig. 13. Should the selected trunk be among the first fifty then the particular test relay corresponding to this trunk in conjunction with relays 1306 and 1307 will determine the operation of the proper frame connector such as 800 so as to associate the marker with the particular office frame in 80 which the divided part of the selected group of district trunks terminates.

Assuming that links 219 and 220 are 85 among the first fifty links and that links 221 and 222 are among the last nineteen links; let it be further assumed that link 219 and trunk 272 provide the first idle cross point 90 through switch 200. Accordingly, test relay 1301, which is connected to link 220 and trunk 273 is operated while relay 1302 is 95 normal. Under these conditions, ground is extended through the contacts of relays 1310 and 1306 to cause the operation of start relay 801. Should the first idle cross point be located among the last nineteen, 100 then the above traced ground is extended through the corresponding test relay of the last nineteen and thence through a break contact of relay 1307 to operate another start relay similar to relay 801.

Returning now to the point where the 105 testing operation was begun and relay 1301 operated, relay 1206 is also operated in a circuit traceable from battery through its winding and normal contacts, conductor 1256, contacts of connector 700, conductor 110 254 to ground at the armature and contact of magnet 228. Relay 1206 immediately 115 closes a locking circuit which extends to the grounded conductor 1257. A circuit is now closed for energizing relays 1308 and 1309, 120 traceable from battery through their windings in parallel, conductor 1352 and thence to ground through the right inner armature and front contact of relay 1206. The operation of relays 1308 and 1309 disconnects 125 the test relays from the district switch. However, those test relays which were operated corresponding to busy cross points, remain locked through their right windings and locking contacts to the grounded conductor 1257. A circuit is now completed from battery through the winding of common relay 1319, winding of relay 1310, left armature and back contact of relay 1302, 130 left armature and front contact of relay

1301, conductor 1353, contacts of connector 750, returning thence to conductor 759, through the normal contact of relays 1216 and 1202, to ground through the right inner armature and front contact of relay 1206. With relay 1310 operated, the grounded conductor 1257 is extended through the left outer armature and contact of relay 1310, right armature and front contact of relay 1306, conductor 1350, contacts of relays 709 and 710, returning by means of the loop 711 to the conductor 757, thence through the winding of start relay 801, conductor 853 to battery at the left normal contacts of relay 1209. It will be noticed that had relay 1311 or relay 1312, corresponding to an idle one of the last 19 cross points, been operated, then ground would have been extended through the left outer armature and contact of one of these last 19 relays thence through the right armature and back contact of relay 1307, left intermediate armature and contact of relay 1306, conductor 1354, contacts of connector 750 and thence by means of loop 712 to the conductor 758 which leads to the winding of a start relay similar to relay 801. Thus it will be seen that the operation of a particular multi-contact relay as 710 in conjunction with the marker test relays determines which office frame connector is to be started in operation. For the purpose of economy and space in the drawing, but one multi-contact relay corresponding to trunks leading to distant offices is shown. However, should another relay similar to relay 710 have been operated, the same conditions would prevail except that the loops at this relay corresponding to loops 711 and 712 would be arranged in such a manner as to cause the operation of a different office frame start relay. When relays 1319 and 1310 operated, a circuit was completed for horizontal magnet 225. This circuit may be traced from battery through the right winding of magnet 225, conductor 261, contacts of connector 700, conductor 769, left intermediate armature and contact of relay 1310 to the grounded conductor 1257. The operation of magnet 225 completes connection through the switch 200 and brings about the release of the district trunk and frame connectors. This release is initiated by relay 1202 which operates in a circuit traceable from battery through its winding, conductor 1267, right armature and front contact of relay 1310, conductor 1355, contacts of connector 750, conductor 262, thence through contacts of switch 200, to the sleeve of trunk 102 which is grounded in the manner described in the above-mentioned application of W. W. Carpenter, Serial No. 703,362, filed April 1, 1924. Relay 1202 locks in a circuit which is completed through the right inner armature and contact of relay 1205, to ground through the right inner armature and back contact of relay 1204. The operation of relay 1202 removes ground from the holding conductor 751 thus causing the release of the connectors 700 and 750 as well as the vertical magnets 257 and 228, the connection through switch 200 being maintained by the continued energization of magnet 225 which is locked through both its windings in series to the grounded sleeve conductor of trunk 102. Relay 1202 also completes a circuit which may be traced from battery through the winding of relay 1205, right inner armature and contact of relay 1214, right outer armature and contact of relay 1202, right outer armature and a contact of relay 1204 to ground at the armature of relay 1203. Relay 1205 locks in series with the winding of relay 1214 which does not operate at this time, however, since it is shunted by the original ground which caused the operation of relay 1205. However, when relay 1205 opens its right outer contacts, relay 1202 releases, and the shunt being removed from relay 1214, this latter relay now operates in series with relay 1205. The translator relays shown in Fig. 11 were released when relay 1206 operated and the operated test relays 1300 released when relay 1205 operated. With relay 1214 operated, a circuit is completed from battery through the winding of relay 1212, right outer armature and front contact of relay 1214, left outer armature and contact of relay 1306, conductor 1356, right outer armatures and back contacts of relays 1202 and 1204 to ground at the armature of relay 1203. Relay 1212 in turn closes an obvious operating circuit for relay 1209. The outgoing marker is now transferred from control of the district trunk group relay 1208 to the office trunk group relay 1207. It will be remembered that office frame start relay 801 operated while the marker was making a test of the district trunks. This relay did not release, however, when connector 750 released, since it is maintained energized in a circuit traceable from battery at the right outer armature and contact of relay 1206, left inner armature and contact of relay 1209, conductor 853, winding and locking contact of relay 801, to the grounded conductor 851. It will be noted that relay 1206 released when ground was removed from conductor 1257, thus causing the release of relays 1308 and 1309. Relay 801, in operating, functions in a manner similar to that described in connection with relay 701, causing the operation of relay 802. With relay 802 operated, vertical magnet 315 energizes in a circuit completed from battery through its winding, outer armature and back contact of relay 321, tip conductor of trunk 272 contacts of switch 200, tip conductor of trunk 102, left armature 130

and front contact of relay 104 through the sender selector switch 150, contacts of connector 600, conductor 651, right normal contacts of relay 1211, left inner armature and 5 front contact of relay 1212, conductor 1259, contacts of relay 802, returning by means of loop 818 to the grounded conductor 851. Magnet 315 operates and rotates the vertical rod 316 to prepare the vertical row of contacts 317. The above traced ground is also extended through the armature and contact of magnet 315 to conductor 350 and thence to battery through the winding of relay 803. Relay 803 and magnet 315 lock to the 10 grounded conductor 851 in a manner similar to that described in connection with relay 707 and magnet 215.

Trunk connector start relay 804 is now energized in a circuit traceable from battery through its winding, conductor 725, 20 next to the outermost armature and contact of relay 1207, conductor 1268 to ground and through the left intermediate armature and contact of relay 818. Relay 804 brings 25 about the operation of relay 806 in a manner similar to that already described for relay 709. Relay 809 now operates in a circuit traceable from battery through its winding, conductor 1265, intermediate armature and contact of relay 1207, conductor 1269, to ground through the intermediate armature and contact of relay 805. With 30 connectors 800 and 850 operated, the test conductors of the links, and of the trunks 35 outgoing from switch 300 are connected to the testing relays 1300 in a manner similar to that described for the district switch 200. When connection has been completed through switch 300, relay 1202 reoperates in 40 substantially the same manner as hereinbefore described. The operation of relay 1202 at this time causes the release of control relay 1201 which in turn brings about the 45 release of the marker and the office and frame connectors. The release of the marker causes the release of the sender connector 600. For the general manner in which the marker releases following operation of the office selector and for the 50 release of the sender connector and for the manner in which the sender now adjusts itself to control the extension of the calling line to the distant office, reference may be had to the application of W. W. Carpenter, 55 Serial No. 703,362, filed April 1, 1924.

Selection through an incoming switch.

Should the called subscriber's line be located in the same office as that of the calling subscriber, selection is completed 60 through a local incoming switch such as 400 in place of switch 300. The sequence of operations in this case is similar to that already described as far as the point where 65 the office code is translated in the marker.

In this case, however, the called line designation as recorded on the register relays 1100, brings about the operation of relay 1217 which is individual to the group of trunks including trunk 275. Since this is a 70 connection of a local character, the relay 1306 remains normal whereas relay 1307 is operated as soon as the marker is attached to the sender. The circuit for relay 1307 extends from battery through its winding, 75 left inner armature and back contact of relay 1306 to the grounded conductor 1258. The operation of connectors 700 and 750 has already been described, but the operation of trunk connector 750 is, in this case, placed 80 under control of the trunk group relay 1217 which brings about the operation of relay 713. A test is now made of the group of trunks including trunk 275. Assuming 85 trunk 275 and link 221 to constitute the first available cross point in switch 200 as already described, and assuming this cross point to be among the last nine, then relay 1304 corresponding thereto is normal while the relays corresponding to the preceding busy cross 90 points are operated. When relay 1319 operates in series with relay 1312, as described hereinbefore, in connection with relays 1319 and 1310, the grounded conductor 1257 is extended through the left outer armature 95 and contact of relay 1312, left inner armature and contact of relay 1307, conductor 1358, contacts of relays 709 and 713, loop 763, and thence in parallel over conductors 100 764 and 765 through contacts of connector 600 to battery through the windings of relays 111 and 112. Relays 111 and 112 immediately lock to the grounded conductor 113. The group of relays 180 form a 105 registering mechanism for recording identification of the incoming switch upon which the divided portion of selected group of local incoming trunks terminates. The reason for having such a record transferred to the sender is conditioned by the fact that the 110 marker is released immediately that connection is completed through switch 200 and prior to the attaching of an incoming marker to the sender.

When horizontal magnet 226 operates to 115 complete the connection through link 222, the release of the marker is brought about by the operation of relay 1202. The manner in which this latter relay operates has already been described. In this instance, however, since no selection is required through an office switch, neither relays 1212 nor 1209 will operate. The operation of relay 1202 at this time therefore breaks the holding circuit for relay 1201 which releases, releasing 120 the marker and sender connector 600 as well as the district frame and trunk connectors. When relay 1319 operated prior to the release of connector 600, ground was extended 125 through the armature of relay 1319, left 130

outer armature and contact of relay 1307, conductor 1362, contacts of connector 600, to battery through the winding of relay 114 which locks to grounded conductor 113.

5 When the sender connector 600 releases and the complete numerical designation has been recorded on the registers 190, ground is extended over conductor 155 through the left armature and contact of relay 114, conductor 156, lower winding of relay 1603 to battery at the armature of relay 1604. In a manner similar to that described in detail in connection with the sender connector 600, relay 1603 locks in series with relay 1604 and brings about the operation of multi-contact relay 1602. Assuming the incoming marker associated with relay 1605 to be busy, then relay 1606 is operated as already described in connection with relay 607. The 10 operation of relay 1606 in turn brings about the operation of relay 1601. It will be observed that the start circuit for the connector 1600 is similar to that of connector 600 which has already been described in detail.

25 With relays 1602 and 1601 operated, the sender is connected to the incoming marker shown in Figs. 14 and 17, and in the manner described in detail in the above-mentioned application of W. W. Carpenter, Serial No. 703,362, filed April 1, 1924, the numerical portion of the called line designation is transferred from the registers 190 of the sender by means of the group of conductors 157 through contacts of connector 1600 to operate corresponding relays of the marker register 1700, 1701, 1702 and 1703. At this time, the record of the incoming frame in which the selected trunk 275 terminates is transferred from the register 180 by means 30 of the group of conductors 158 and connector 1600 to the incoming frame register 1750. Since the incoming switch was identified by the operation of relays 111 and 112, ground is now extended through the right armatures 35 and front contacts of these latter relays over conductors 159 and 169 to operate relays 1704 and 1706. When all the register relays have been operated as described in the above-mentioned application of W. W. Carpenter, Serial No. 703,362, filed April 1, 1924, relay 1707 operates, in turn operating relay 1708 which locks to conductor 1751 which is grounded as hereinafter described.

40 Let it be assumed that the called line designation as transferred to the incoming marker registers causes the operation of relay 1714 of the units register 1700, relays 1716 and 1723 of the tens register 1701, relay 1718 of the hundreds register 1702 and relay 1710 of the thousands register 1703.

45 As soon as the sender was connected to the incoming marker, holding relay 1401 operated in a circuit traceable from battery through its winding, conductor 1650, through contacts of connector 1600 to ground in the associated sender. Relay 1401 locks in a circuit traceable through its armature and locking contact, right armature and back contact of relay 1402, to ground at the left armature of relay 1403. A circuit is now completed 50 for relay 901 as determined by the setting of the frame register 1750. The circuit for relay 901 may be traced from battery through its winding, conductor 951, right outer armature and front contact of relay 1706, right outer armature and back contact of relay 1705, right outer armature and front contact of relay 1704, right outer armature and back contact of relay 1709, upper outer armature and contact of relay 1708, conductor 80 1751, right inner armature and contact of relay 1405, right outer armatures and contacts of relay 1410 and 1411, right inner armature and contact of relay 1442 to ground at the armature of relay 1401. A circuit is now completed from battery through the lower winding of relay 902 armature and front contact of relay 901, armature and back contact of relay 903, left armature and back contact of relay 904, to ground at the 85 armature of relay 905. The operation of relay 902 completes a circuit which may be traced from battery through the winding of slow-release relay 905, right armature and back contact of relay 904, lower armature 90 and front contact of relay 902, conductor 952, right outer armature and contact of relay 1442, to ground through the intermediate armature and contact of relay 1401. Relay 905 opens the circuit of relay 902 which being slightly slow-to-release remains operated until it is locked in a circuit in series with the winding of relay 904 leading through the front contact of relay 905. Relay 904 100 operates. The operation of relay 904 breaks the energizing circuit for slow-release relay 905. When relay 905 releases, ground is extended through its back contact, left armature and front contact of relay 904, intermediate armature and contact of relay 902, 105 to battery through the winding of relay 906. Relays 904 and 902 remain locked in a circuit leading through the right front contact of relay 904, lower contact of relay 902 to grounded conductor 952. The next operation to take place is the energizing of vertical magnet 409 which controls the vertical row of contacts 401 of the incoming switch 110 400 in which trunk 275 appears. The circuit for operating vertical magnet 409 is closed upon the operation of relay 311. The circuit for operating relay 311 may be traced from battery through its left winding, outer armature and back contact of relay 301, tip conductor of trunk 275, contacts of switch 115 200, tip conductor of trunk 102, left armature and front contact of relay 104, contacts of sender selector 150, conductor 163, contacts of sender connector 1600, conductor 1451, normal contacts of relay 1404, conductor 953, 120 200, tip conductor of trunk 102, left armature and front contact of relay 104, contacts of sender selector 150, conductor 163, contacts of sender connector 1600, conductor 1451, normal contacts of relay 1404, conductor 953, 125 200, tip conductor of trunk 102, left armature and front contact of relay 104, contacts of sender selector 150, conductor 163, contacts of sender connector 1600, conductor 1451, normal contacts of relay 1404, conductor 953, 130

lower armature and contact of relay 906 to the grounded conductor 952. Relay 311 connects ground through its intermediate armature and contact to conductor 352 and 5 thence to battery through the winding of magnet 409. Magnet 409 rotates bar 407 and prepares the contacts in the vertical row 401.

The multi-contact relay 907, individual to 10 the portion of selector switch 400 in which trunk 275 terminates, is now energized in a circuit traceable from battery through the winding of relay 907, conductor 456 to ground at the armature and contact of relay 311. A circuit is now completed from 15 battery through the winding of relay 1404, conductor 962, contacts of connector 900, conductor 452 to ground at the armature of magnet 409. The operation of relay 1404 20 provides a holding circuit for magnet 409 and relay 907 which may be traced from battery through the windings of magnet 409 and relay 907 in parallel, contacts of connector 900, conductor 964, right armature and 25 front contact of relay 1404, conductor 953, lower armature and contact of relay 906 to grounded conductor 952.

Assuming line 519 to be the called line, the 30 next step in the sequence of operations is the association of the marker with the particular one of the final translators which controls the operation of the group of final switches having access to the called line. The choice of this final translator is determined 35 by the thousands register 1703 and since relay 1710 is operated, a circuit is completed for start relay 1501 which may be traced from battery through its winding, conductor 1551, right armature and front 40 contact of relay 1710, right armature and back contacts of relays 1711 and 1712, inner armature and contact of relay 1708, conductor 1752, outer armature and contact of relay 902 left armature and front contact of 45 relay 904 to ground at the armature of relay 905. A circuit is now completed from battery through the left winding of relay 1502, left armature and front contact of relay 1501, right armature and back contact of relay 50 1504, to ground at the armature of relay 1503. Relay 1502 immediately locks through its right winding in series with the winding of relay 1504 which operates. Relay 1504 breaks the original energizing circuit of relay 1503 which begins to release. When relay 1503 closes its back contact, 55 ground is connected through the right armature and front contact of relay 1504, right outer armature and contact of relay 1502 to battery through the winding of relay 1505. When relay 1503 releases relays 1502 and 60 1504 lock through the left front contact of relay 1504 and the left contact of relay 1502 to ground at the contact of relay 1401. Relay 1505 extends the conductors from the

marker to the final translator shown in Fig. 10.

Since thousands register relay 1719 is normal, a circuit is completed from battery through the winding of relay 1003, left inner armature and contact of relay 1013, contacts of connector 1500, conductor 1757, right armature and back contact of relay 1719, upper inner armature and contact of relay 1708 to ground over conductor 1752 as above 75 traced. Relay 1003 operates whenever the thousands digit of the called line designation as recorded on register 1703 is odd, whereas relay 1002 operates when the thousands digit is even. The registration of the thousands 80 digit in conjunction with relay 1003 now controls the operation of one of the multi-contact relays 1004, 1005, etc. Accordingly, a circuit is completed from battery through the winding of relay 1004, outermost armature and contact of relay 1003, contacts of connector 1500, conductor 1758, right outer armature and front contact of relay 1718, right outer armature and back contact of relay 1721, outer armature and front contact 90 of relay 1708 to grounded conductor 1751.

Since units register relay 1713 is normal, ground is extended from its right armature and contact over conductor 1753, contacts of connector 1500, winding of relay 1006, returning thence through contacts of connector 1500, conductor 1759, right armature and back contact of relay 1722 to ground as above traced. Relay 1006 corresponds to called line designation with units less than 100 5 and thousands digit odd. A circuit is now completed for operating vertical magnet 515 which may be traced from battery through the winding thereof, conductor 551, contacts of the relays 1004 and 1006, conductor 1051, contacts of connector 1500, conductor 1754, right inner armatures and front contacts of relays 1723 and 1716, right inner armatures and back contacts of relays 1724 and 1725 to the grounded conductor 1769. A locking 105 circuit is completed for magnet 515 which may be traced through its outer armature and locking contact, conductor 557, conductor 955, right armature and back contact of relay 1428, right armature and back contact 110 of relay 1444, outermost armature and back contact of relay 1410, right armature and back contact of relay 1411, inner armature and back contact of relay 1442 to ground at the armature of relay 1401. 115

Since the units digit determines the location of the wanted line in section 522 of switch 500, it will be necessary to operate multi-contact relay 1007 which is individual thereto. This circuit may be traced from 120 battery through the winding of relay 1007, contacts of connector 1500, right inner armature and back contact of relay 1715, right armature and front contact of relay 1714 to grounded conductor 1769. Relay 1007 125 130

immediately locks through its winding and locking contact to ground over conductor 955 as hereinbefore traced.

The connection of the marker with the group of trunks interconnecting switches 400 and 500 will now be described. Since there are a number of groups of trunks leading from the incoming switch to the final switches, it is necessary that the marker be connected to the particular group which leads to the final switch 500 containing the line 519. The identity of this group of trunks may be had from the incoming frame connector 900, and the identity of the final switch may be had from the translator. Accordingly, multi-contact relay 908, which is individual to the group of trunks extending between switches 400 and 500 and including trunks 460 and 461 is operated. The circuit for relay 908 may be traced from battery through its winding, outer armature and contact of relay 909, conductor 954, contacts of connector 1500, conductor 1552, contacts of relays 906 and 907, returning thence to the grounded conductor 955. Relay 908 connects ground through its lower armature and contact, conductor 956, through the contacts of connector 1500 to battery through the winding of relay 1506. At the time vertical magnet 515 operated, a circuit was completed for relay 1008, which is individual to the final switch 500, which may be traced from battery through its winding, outer armature and contact of relay 1014, conductor 553, through the outer armature and contact of magnet 515 to ground over conductor 557.

The next step is the testing of the links in the switches 400 and 500 as well as the group of trunks including trunks 460 and 461. The marker is provided with a series of testing relays 1470 comprising a sufficient number of these relays for testing the horizontal links of switches 400 and 500 and the trunks interconnecting these switches. The double wound relays 1421, 1422, etc., by means of their left windings test the links of switch 400 while their right windings are for the purpose of testing outgoing trunks. If either a link or a trunk or both a link and a trunk are busy, the corresponding test relay operates. Relays 1424, 1425 and 1426, pertain to corresponding links in switch 500. Assuming first that links 405 at the incoming switch, trunk 460, and link 505 of the final switch are simultaneously busy; a circuit is therefore completed from battery through the left winding of test relay 1421, innermost armature and back contact of relay 1427, conductor 926, contacts of connector 900, conductor 418 to the grounded sleeve conductor of link 405. Another circuit is completed from battery through the right winding of relay 1421, next to the innermost armature and back contact of relay 1427, right

inner armature and back contact of relay 1420, conductor 1453, contacts of connector 1500, contacts of relay 908, conductor 463, to the sleeve conductor of trunk 460. Link 505 being busy also, a circuit is closed for operating relay 1424. This circuit may be traced from battery at the left outer armature and contact of relay 1430, winding of relay 1424, conductor 1454, contacts of relay 1506, contacts of connector 1500, conductor 1063, contacts of relay 1007, contacts of relay 1008, conductor 525 and thence to the grounded sleeve conductor of link 505. Had the link 405 and trunk 460 been idle, the busy condition of link 505 in causing the operation of relay 1424, also will bring about the operation of relay 1421. The circuit in this case may be traced from battery through the right winding of relay 1421, left inner armature and contact of relay 1424, right outer armature and back contact of relay 1430 to the grounded conductor 1432.

If, however, the link 405 and trunk 460 and link 505 are idle at the same time, relays 1421 and 1424 remain normal. A circuit is therefore closed for magnet 412 which controls vertical row of contacts 404 in which the selected group of trunks, including trunk 460, appears. The circuit for operating magnet 412 may be traced from battery through its winding, conductor 454, contacts of connector 900, conductor 958, contacts of connector 1500, conductor 1553, contacts of relay 908, conductor 959, contacts of relay 1007, contacts of relay 1008, conductor 1053, contacts of connector 1500, contact of relay 1506, conductor 1554, right armatures and back contacts of relays 1428, 1444, 1410, 1411, right inner armature and back contact of relay 1442 to ground at the armature of relay 1401. Magnet 412 rotates bar 416 to prepare the contacts in vertical row 404. Relay 1430 now operates in a circuit traceable from battery through its winding, left armature and contact of relay 1402, conductor 1452, contacts of connector 900, lower armature and contact of magnet 412, conductor 455, contacts of connector 900, to the grounded conductor 952. With relay 1430 operated, circuits are closed for operating relays 1427, 1420 and 1405. Relay 1427 operates in a circuit through the right outer armature and front contact of relay 1430 to the grounded conductor 1432. A circuit for relay 1405 may be traced from battery through its winding, winding of relay 1420, left armature and back contacts of relays 1421 and 1435, right inner armature and contact of relay 1410, right outer armature and front contact of relay 1430 to the grounded conductor 1432.

During the latter operations, a test is also made to ascertain the condition of the called subscriber's line. At the time the connect-

ing devices, 1010 and 1020 are operated magnet 510 is energized in a circuit traceable from battery through its right winding, conductor 567, contacts of relays 1008 and 1007 to the grounded conductor 955. Magnet 510 operates the common test link 507 which connects with the sleeve conductor of the line 519. When relay 1430 later operates, a test circuit is completed from battery through the winding of relay 1411, right inner armature and contact of relay 1430, intermediate armature and back contact of relay 1410, left armature and contact of relay 1436, conductor 1437, contacts of connector 1500, conductor 1555, contacts of relay 1008 and thence through the test link to the sleeve conductor of line 519. Assuming line 519 to be idle, relay 1411 fails to operate in this last traced circuit. With relay 1420 operated as above explained, a circuit is now completed for operating vertical magnet 512, associated with the vertical row of contacts 504 in which trunk 460 appears. This circuit may be traced from battery through the winding of magnet 512, conductor 558, contacts of relay 1008, conductor 1059, contacts of relay 908, conductor 966, contacts of connector 1500, contacts of relay 1506, conductor 1439, right outer armature and contact of relay 1420, right armatures and back contacts of relays 1428, 1444, 1410, 1411, right inner armature and back contact or relay 1442 to ground at the armature of relay 1401. Magnet 512 rotates bar 513 and prepares the contacts in the vertical row 504. Magnet 512 also causes the operation of horizontal magnets 417 and 509. The circuit for magnet 417 may be traced from battery through its right winding, conductor 419, contacts of connector 900, left outer armature and contact of relay 1420, conductor 1440, contacts of connector 1500, conductor 1056, contacts of relay 1008, conductor 1061, lower armature and contact of magnet 512, lowermost armature and contact of magnet 515 to grounded conductor 557. Magnet 417 operates bar 420 and establishes connection between trunk 275 and trunk 460 by means of link 405. The circuit for operating magnet 509 may be traced from battery through the right winding thereof, conductor 525, contacts of relays 1008 and 1007, conductor 1063, contacts of connector 1500, contacts of relay 1506, conductor 1556, left outer armature and contact of relay 1420 to ground as above traced. Magnet 509 operates bar 534 and completes connection of trunk 460 to the line 519 by means of link 505. When magnet 417 operates, it causes the actuation of relay 301 in a circuit traceable from battery through a winding of the said relay, sleeve conductor or trunk 275, contact of switch 400 to ground. Relay 301 immediately locks to ground through the con-

tacts of switch 200 to the grounded sleeve conductor of trunk 102. A holding circuit for magnet 417 is now completed through both windings in series, contacts of switch 400, to the grounded sleeve conductor of trunk 275. As soon as horizontal magnet 417 operated, a circuit was completed from battery at the normal contacts of relay 424, through the right winding thereof, thence through the contacts of switch 400 to the grounded sleeve conductor of trunk 275. Relay 424 locks by means of its right winding and locking contact in series with the winding of relay 425. Relay 425 at its right outer armature connects ground to the sleeve conductor of trunk 460 thus providing a holding circuit for magnet 509 traceable through both windings of this magnet in series.

With relay 425 operated, a circuit is completed for actuating the marker release relay 1402. This circuit may be traced from battery through the winding of relay 1402, right inner armature and front contact of relay 1420, conductor 1453, contacts of connector 1500, contacts of relay 908, conductor 463 to ground at the outer armature of relay 425. Relay 1402 in operating opens the holding circuits of relays 1430 and 1401 which relays release and in turn remove ground from the various holding conductors to permit restoration to normal of the marker and associated equipment. Upon the release of the marker, magnets 409, 412, 510, 512 and 515 are restored and the associated bars return to normal. Connection through the switches 400 and 500 is now maintained by the continued energization of magnets 417 and 509.

The incoming marker and controlling equipment including the translator shown in Fig. 10, have been restored and may be employed in controlling the extension of other calling lines. The circuits are now in readiness to apply ringing current to the called line. When the sender releases, in the manner described in detail in the above-mentioned application of W. W. Carpenter, relay 103 retracts its armatures, causing the operation of relay 106. Relay 106 closes an obvious operating circuit for slow release relay 105 which maintains a busy potential on the sleeve conductors of the various trunks.

When relay 301 operated and completed the circuit of the sleeve conductor of the trunk 275, ground was extended through the contacts of relay 309 to operate relay 308. The operation of relay 308 connects ringing current through the winding of relay 309, lower armature and front contact of relay 308, ring conductor of trunk 275, contacts of switch 400, ring conductor of trunk 460, contacts of switch 500 through the ringing apparatus at the called subscriber's sta-

tion, returning thence over the tip side of the trunks to ground at the upper armature and front contact of relay 308. When the called subscriber answers, the resistance included in this last traced circuit is reduced and relay 309 operates, thus breaking the circuit for relay 308 which releases. The release of relay 308 completes the connection of the called line with the right winding of 10 repeating coil 360 operating relay 310.

For a more complete description of the arrangement and operation of the incoming markers, translators and connecting devices, reference may be had to the application of 15 S. B. Williams, Serial No. 707,795, filed April 21, 1924.

At the termination of conversation, when the parties have replaced the receivers on their respective switchhooks, relay 106 releases, in turn releasing relay 105. Relay 20 105 removes ground from the sleeve conductor of trunk 102 whereupon magnet 226 deenergizes, releasing switches 200 and 400. The removal of ground from the sleeve conductor trunk of 275 also causes relays 424 and 425 to release. Relay 425 opens the 25 circuit of magnet 509 which deenergizes and releases switch 500.

30 Connection to a P. B. X. line.

Should the designation as dialled by the calling subscriber be that allotted to a group of lines leading to a private branch exchange, the sequence of operations is similar 35 to that already described in connection with a local call as far as the point where the test horizontal magnet 510 is operated. The circuits are so arranged that the first line of a group of lines leading to a P. B. X. is given a directory number, the other lines of 40 the group being unnumbered. For example, assume line 520 to be the first of a group of lines leading to the P. B. X. 590. Let it also be assumed that the units digit of this 45 P. B. X. line designation is such as to cause units register relay 1715 to be operated. In this case, the final group relay 1009 is operated in place of relay 1007. The circuit of relay 1009 may be traced from battery 50 through its winding, conductor 1064, contacts of connector 1500, right outer armature and front contact of relay 1715, right armature and back contact of relay 1714 to 55 grounded conductor 1769. Relay 1009 immediately locks through its winding and locking contact to the grounded conductor 955. A circuit is now closed for test horizontal magnet 526 associated with the portion 60 524 of the final switch. The circuit for magnet 526 may be traced from battery through the right winding thereof, conductor 559, contacts of relays 1008 and 1009 to ground over conductor 955. Assuming the 65 first line 520 to be busy, then relay 527 individual thereto is operated and when mag-

net 526 operates, connection is completed through the test link 531 to the distributing block 578. The grounded conductor 557 is now extended through the lowermost armature and contact of magnet 515, lower 70 conductor to test link 531 and thence by means of the block 578 to battery through the winding of relay 521. Relay 521 closes a locking circuit traceable from battery through its winding and locking contact, 75 conductor 565, contacts of connector 1500 and thence to the grounded conductor 1432. When relay 521 operates, it also extends the last traced ground through its left intermediate armature and contact, thence 80 over conductor 566, contacts of connector 1500, left armature and contact of relay 1409 to battery through the winding of relay 1410. Relay 1410 in operating removes ground from conductor 1751, causing the release of the translator relays shown in Fig. 10 and relays 908 and 1009. Vertical magnets 412 and 515 also release, as does test magnet 526. The connector 1500, however, does not release at this time, since it is maintained actuated under the control of relay 1401. When relay 1430 releases, as a result of the release of magnet 412, a circuit is completed from battery through the winding 85 thereof, left inner armature and contact of relay 1430, left armature and contact of relay 1410 to the grounded conductor 1432. 90

Assuming line 529, which is the second 95 of the P. B. X. groups to be idle, a circuit is completed for vertical magnet 576 which may be traced from battery through the winding thereof, left armature and back contact of relay 528, left armature and front contact of relay 527, right inner armature 100 and contact of relay 521, conductor 561, contacts of connector 1500, conductor 1551, left intermediate armature and contact of relay 1428 to grounded conductor 1432. Magnet 516 immediately locks through its winding 105 and locking contact, thence by means of conductors 557 and 955 through the right armature and front contact of relay 1428 to ground over conductor 1432. Magnet 516 also extends this last traced ground through 110 its lowermost armature and contact over conductor 553 to operate relay 1008. When relay 1428 operated, it completed a circuit from battery through the winding of relay 1012, conductor 561, contacts of connector 1500 to ground through the left intermediate armature and contact of relay 1428. A circuit is now completed for relay 1007 115 which may be traced from battery through its winding, intermediate armature and contact of relay 1012, conductor 1065, right armature and back contact of relay 528, right inner armature and front contact of relay 527, right outer armature and contact 120 of relay 521, to ground over conductor 554. 125

In a manner similar to that already described, a circuit is closed for operating vertical magnet 412.

The testing equipment is now connected 5 to the links of switches 400 and 500 as well as to the group of trunks including trunks 460 and 461, and these switches are operated in the manner already described to extend the calling line to the P. B. X. line 529.

10 Should the first P. B. X. line 520 have been idle when test magnet 526 operated, then relay 527 is normal and the grounded conductor 557 is extended through the lowermost armature and contact of magnet 15 515, through test link 531 to operate relay 521 as already described. This same ground is also extended through the left armature and contact of relay 568, left outer armature and back contact of relay 527, conductor 569, to battery through the winding of relay 1409. The operation of relay 1409 in this case, opens the circuit of relay 1410 which is prevented from operating. Under these conditions, holding ground is maintained 20 on conductor 1751, thus holding the translator and marker relays operated. Consequently, magnets 412 and 515 do not release until the calling line is extended to the line 529 in the manner already described.

30 From the latter description it will be seen therefore that when the first line of a group of P. B. X. lines is idle, connection is completed thereover to the P. B. X. in a manner similar to that described for a local call. However, should the first line be busy, a portion of the connection is released and a new record automatically set up in the marker to select a succeeding idle line of 35 the P. B. X. group.

40 What is claimed is:—

1. In a telephone exchange system, first 45 selective switches, a plurality of second selective switches, groups of trunks each group extending between one of said first selective switches and a plurality of said second selective switches, a common controlling mechanism associable in succession with said first and second selective switches, testing means in said common controlling 50 mechanism for testing said groups of trunks, a selectively operable connecting device for associating a particular one of said groups of trunks with said testing means, means for selecting an idle trunk in said 55 group of trunks, and means dependent upon the selective operation of said connecting device and the condition of said testing means for identifying the particular one of 60 said second selective switches to which the selected idle trunk leads.

2. In a telephone exchange system, telephone lines, a plurality of first selective switches, means for extending said lines to 65 said switches, a common testing and control-

ling mechanism, a plurality of second selective switches, trunks extending between said first and said second selective switches, a variably operable connecting device for associating said testing and controlling mechanism with certain of said trunks, means for selecting a trunk at one of said first selective switches, said trunk leading to a particular one of said second selective switches, and means controlled by the conjoint operation 70 of said connecting device and the conditions of said testing means for identifying the particular second selective switch to which the selected trunk leads.

3. In a telephone exchange system, telephone lines, a plurality of first selective switches, means for extending said lines to said switches, a common testing and controlling mechanism, a plurality of second selective switches, groups of trunks extending between said first and said second selective switches, a first variably operable connecting device for associating said testing and controlling mechanism with a particular one of said groups of trunks, means for selecting a trunk in said group of trunks said trunk leading to a particular one of said second selective switches, a second variably operable connecting device and means controlled by the conjoint operation of said 80 first connecting device and the condition of said testing mechanism for determining the operation of said second connecting device to thereby associate said common controlling mechanism with the particular 85 second selective switch to which the selected trunk leads.

4. In a telephone exchange system, a plurality of first selective switches, a plurality of second selective switches, a common controlling and testing mechanism associable with said first and said second selective switches for controlling the operation thereof, a group of trunks extending between one of said first selective switches and a plurality of said second selective switches, a first variably operable connecting device for associating said group of trunks with said 90 controlling and testing mechanism, a second variably operable connecting device for 95 associating a particular one of said second selective switches, with said controlling and testing mechanism, and means dependent upon the mode of operation of said first connecting device and the condition of said testing mechanism for determining the mode of operation of said second connecting device.

5. In a telephone exchange system, a first selective switch, a second selective switch, 100 groups of trunks extending between said first and said second selective switches, a common controlling mechanism associable in succession with said first and said second selective switches for controlling the oper- 105

- ation thereof, a first variably operable connecting device, testing means located in said common controlling mechanism, means for operating said first connecting device to associate said testing means with a particular one of said groups of trunks, means for selecting an idle trunk in said one of said groups of trunks, a second variably operable connecting device, and means dependent upon the mode of operation of said first connecting device and the condition of said testing means for determining the mode of operation of said second connecting device.
6. In a telephone exchange system, calling lines, first selective switches, second selective switches, a register sender accessible in common to a plurality of calling lines, a controlling mechanism common to a plurality of said first selective switches, trunks extending between one of said first selective switches and a plurality of said second selective switches, a first variably operable connecting device for associating said common controlling mechanism, with certain of said trunks, testing means located in said common controlling mechanism, means dependent upon the mode of operation of said first connecting device and the condition of said testing means for transferring to said sender an identification of a particular one of said second selective switches, a second variably operable connecting device, and means under control of the recorded identification in said sender for determining the mode of operation of said second connecting device.
7. In a telephone exchange system, telephone lines, first selective switches, second selective switches, a common register sender for recording designations of wanted telephone lines, a group of trunks extending between one of said first selective switches and a plurality of said second selective switches, testing means for testing the trunks in said group, a selectively operable connecting device for associating said group of trunks with said testing means, means under control of a recorded designation in said sender for operating said connecting device, means for selecting an idle trunk in said group of trunks, means dependent upon the selective operation of said connecting device and the condition of said testing means for recording in said sender an identification of the particular second selective switch to which said selected trunk leads.
8. In a telephone exchange system, telephone lines, first selective switches, second selective switches, a common register sender for recording designations of wanted telephone lines, a controlling mechanism accessible in common to a plurality of said second selective switches, a group of trunks extending between one of said first selective switches and a plurality of said second selective switches, testing means for testing the trunks in said group, a selectively operable connecting device for associating said group of trunks with said testing means, means under control of a recorded designation in said sender for operating said connecting device, a second selectively operable connecting device for associating said group of trunks with said testing means, means under control of a recorded designation in said sender for operating said connecting device to associate certain of said trunks with said common testing mechanism, a controlling mechanism common to a number of said second selective switches, means dependent upon the selective operation of said first connecting device and the condition of said second connecting device for determining the selective operation of said second connecting device.
9. In a telephone exchange system, telephone lines, first selective switches, second selective switches, a common register sender for recording designations of wanted lines, a controlling mechanism accessible in common to a plurality of said second selective switches, a group of trunks extending between one of said first selective switches and a plurality of said second selective switches, testing means for testing said group of trunks, a first selectively operable connecting device for associating said group of trunks with said testing means, means under control of a recorded designation in said sender for operating said connecting device, a second selectively operable connecting device for associating said common controlling mechanism with said second selective switches, means for selecting an idle trunk in said group of trunks, and means dependent upon the selective operation of said first connecting device and the condition of said testing means for determining the selective operation of said second connecting device.
10. In a telephone exchange system, telephone lines, first selective switches, second selective switches, trunks extending between said first and said second selective switches, a register sender for recording the designations of wanted lines, a common testing mechanism for testing the condition of said trunks, a first variably operable connecting device, a second variably operable connecting device, means controlled by a recorded designation in said sender for selectively operating said first connecting device to associate certain of said trunks with said common testing mechanism, a controlling mechanism common to a number of said second selective switches, means dependent upon the selective operation of said first connecting device and the condition of said second connecting device for determining the selective operation of said second connecting device.

testing mechanism for recording in said sender an identification of a particular one of said second selective switches, and means under control of the recorded identification for selectively operating said second connecting device to thereby associate a particular second selective switch with said controlling mechanism.

11. In a telephone exchange system, subscriber's lines, first selective switches, second selective switches, a common controlling mechanism for said first and said second selective switches, a plurality of trunks extending between one of said first selective switches and a plurality of said second selective switches, a common connecting device comprising a plurality of rows of contacts and operating means for each row, means for actuating said operating means to associate said common controlling mechanism with certain of said plurality of trunks, testing means in said common controlling mechanism for testing said trunks, means for selecting an idle one of said trunks, means operable in accordance with the actuation of said operating means and the condition of said testing means for identifying the particular second selective switch in which said selective idle trunk leads.

12. In a telephone exchange system, a selective switch, second selective switches, a register sender, a first marker for controlling said first switch, a second marker for controlling said second switches, a group of trunks extending from said first switch to said second switches, means for operating said first switch to select a trunk to one of said second switches, means in the first marker for determining which trunk is selected and for transferring a record thereof to the sender, means for connecting said second marker to any one of said second switches to control the same, and means for transferring said record from the sender to said second marker to selectively actuate said connecting means to connect said second marker to the particular second switch to which leads the selected trunk.

13. In a telephone exchange system, subscriber's lines, first selective switches, second selective switches, a register sender, a first controlling mechanism accessible in common to a plurality of said first selective switches, a second controlling mechanism accessible in common to a plurality of said second selective switches, a group of trunks extending between one of said first selective switches and a plurality of said second selective switches, a connecting device comprising a plurality of rows of contacts and operating means for each row, means under control of said sender for actuating said operating means to associate said first controlling mechanism with a particular one of said first selective switches, means in said first

controlling mechanism for testing the trunks in said group, means for selecting an idle one of said trunks, means operable in accordance with the actuation of said operating means and the condition of said testing means for recording in said sender a record of the particular second selective switch to which the selected idle trunk leads, and means under control of the recorded identification for selectively associating said second controlling mechanism with said particular second selective switch.

14. In a telephone exchange system, a selective switch, lines appearing in said switch, certain of said lines being numerically designated others of said lines being non-numerically designated, means for operating said switch to select a numerically designated line to thereby identify a group of non-numerically designated lines, means for testing the condition of the selected numerically designated lines and all the identified non-numerically designated lines, means effective when the numerically designated line is busy for partially releasing said extended connection to automatically reoperate said switch to extend a connection to an idle one of said non-numerically designated lines.

15. In a telephone exchange system, a selective switch, groups of lines appearing in said switch, each of said groups comprising a numerically designated line and a plurality of non-numerically designated lines, means for operating said selective switch to seize a numerically designated line of a particular one of said groups of lines, means effective when the numerically designated line of the group is busy for partially releasing said selective switch and for automatically reoperating the said switch to thereby seize an idle one of said non-numerically designated lines.

16. In a telephone exchange system, a selective switch, groups of lines appearing in said switch, each of said groups comprising a numerically designated line and a plurality of non-numerically designated lines, means for operating said selective switch to seize a numerically designated line of a particular one of said groups of lines, and means effective when the numerically designated line of the group is busy for partially releasing said selective switch and for automatically reoperating the said switch to thereby seize the first idle one of said non-numerically designated lines.

17. In a telephone exchange system, a selective switch, a group of lines appearing in said switch, the first line of said group being numerically designated, the remaining lines of said group being non-numerically designated, means for extending a connection through said switch to the numerically designated line, and means effective when

the numerically designated line is busy for partially releasing said selective switch and for automatically reoperating said switch to complete the previously extended connection to a non-numerically designated line.

18. In a telephone exchange system, a selective switch, a private branch exchange, a group of lines appearing in said switch and leading to said private branch exchange, said group of lines comprising a first line which is numerically designated and other lines which are non-numerically designated, means for extending a connection through said switch to the numerically designated line, and the means effective when the numerically designated line is busy for partially releasing said selective switch and for automatically reoperating the said switch to complete the previously extended connection over a non-numerically designated line.

19. In a telephone system, first and second selective switches, a register sender, a first marker for controlling said first switches, a second marker for controlling said second switches, trunks extending from said first switches to said second switches, means for operating one of said first switches to select a trunk leading to one of said second switches, means in the first marker for transferring to the sender a record identi-

fying the trunk employed in extending the connection, and means for transferring said record from the sender to said second marker to determine the association of said second marker with the proper one of said second selective switches.

20. In a telephone system, first and second selective switches, a register sender, a first marker associative with said first switches for controlling the same, a second marker associative with said second switches for controlling the same, trunks extending from the first to the second switches, means for operating a first switch to select a trunk leading to one of the second switches, means in the first marker for determining the trunk selected and for transferring to the sender a record thereof, means for releasing the first marker, means for thereupon associating said sender with the second marker and for transferring to the second marker the record identifying said trunk, and means controlled in accordance with said record for associating the second marker with the particular second selective switch to which said trunk leads.

In witness whereof we hereunto subscribe our names this 19th day of June A. D., 1924.

SAMUEL B. WILLIAMS.
EARL S. GIBSON.
